MEANS AND METHOD OF APPLYING LABELS

Ray Stanton Avery, Los Angeles, Calif.

Original application May 14, 1941, Serial No. 393,359. Divided and this application April 14, 1943, Serial No. 482,968

8 Claims. (Cl. 216—62)

This invention relates to a method and apparatus for applying labels carrying trade-marks, advertising or identifying media to elongated articles, such as wiring, rope, garden hose, cables, and the like. The application is in the main divisional of my copending application Serial No. 393,359, filed May 14, 1941, entitled Label dispenser.

An object of the present invention is to provide a method and apparatus whereby the elongated article to which the labels are to be applied at intervals can be fed adjacent a dispensing mechanism. A continuous backing on which the labels are temporarily mounted is fed to the dispensing mechanism and the labels are consecutively detached from the backing by the dispenser and deposited on and applied to the elongated article as it is fed past the dispenser.

Another object of the invention is to provide a method and apparatus whereby labels may be applied to an elongated article, such as wire, rope, cable, and the like at regular spaced intervals with great facility and at a high rate of speed.

With the foregoing and other objects in view, which will be made manifest in the following detailed description and specifically pointed out in the appended claims, reference is had to the accompanying drawing for an illustrative embodiment of the invention, wherein:

Figure 1 is a schematic view illustrating the apparatus embodying the present invention;

Fig. 2 is a sectional view taken substantially upon the line 2—2 upon Fig. 1 in the direction indicated, parts being broken away and shown in vertical section;

Fig. 3 is a view taken substantially upon the line 3—3 upon Fig. 1 in the direction indicated;

Fig. 4 is a sectional view taken substantially upon the line 4—4 upon Fig. 1 in the direction indicated;

Fig. 5 is a sectional view taken substantially upon the line 5—5 upon Fig. 1 in the direction indicated;

Fig. 6 is an enlarged sectional view through the dispensing mechanism taken substantially upon the line 6—6 upon Fig. 2 in the direction indicated; and

Fig. 7 is a sectional view similar to Fig. 2, illustrating a modified form of dispensing mechanism that may be employed.

Referring to the accompanying drawing wherein similar reference characters designate similar parts throughout, the apparatus illustrating the embodiment of the present invention comprises a label dispensing mechanism or device, generally

indicated at 10. This device in the preferred form of construction comprises an arcuate member providing two concentric arcuate passages 11 and 12 between which at the rear end of these passages there is disposed a relatively sharp peeling edge 13. A continuous label strip comprising a continuous backing 14 is fed to the dispenser over one or more idler rollers 15 and is trained into the outer or uppermost passage 11. On this backing there is temporarily mounted a plurality or a row of individual labels 16 which are preferably formed of paper but which may be formed of other flexible materials.

The labels 16 may have printed thereon trademarks, advertising information, identifying media, or any other printed matter. These labels are attached to the backing by means of a normally tacky adhesive commonly referred to in the art as a pressure-sensitive adhesive. The adhesive is applied to the under-surfaces of the labels and has a greater affinity for the labels than for the backing so that when the labels are peeled or stripped from the backing the adhesive is removed with them.

The backing 14 is trained around the relatively sharp edge 13 and is extended forwardly through the lower or inner passage 12 and may be trained over one or more idler rollers 17 to a windup reel (not shown) which winds up the backing and which either intermittently or continuously draws the backing rearwardly through passage 11 around the sharp edge 13 and forwardly through the inner passage 12.

It will be noted that in the preferred form of construction both the backing and the label is transversely arched or flexed so that at the time the backing is peeled from the label as illustrated in Fig. 6, the label is in the arched or flexed position which tends to stiffen it and thus resists any tendency of the label to follow the backing around the peeling edge 13.

The elongated article, such as wire, rope, cable, garden hose or the like is indicated at 18 and is fed preferably continuously beneath the dispensing device 10. It may be trained over one or more idler rollers 19. As the labels are consecutively peeled from the backing by drawing the backing around the peeling edge 13 they are freed from the backing and allowed to drop or fall onto the elongated article 18 as indicated at 20. The pressure-sensitive adhesive being normally tacky, causes the label to stick thereto temporarily. This is somewhat assisted by the fact that the adhesive is freshly exposed by peeling the backing therefrom immediately prior to the label contacting the

article 18. The article 18 is then caused to pass beneath a grooved roll 21 which serves to bend the sides of the label downwardly about the elongated article as illustrated in Fig. 3. It also serves to press the label firmly against the top of the article 18. If the article 18 is of relatively large diameter, such as for example in the case of garden hose or heavy cable, the width of the label may be equal to or less than one-half the circumference of the article. In this event the roll 21 may alone suffice to firmly apply the label to the article. On the other hand, if the wire or rope is of relatively small diameter so that the width of the label is greatly in excess of the circumference of the article additional rolls 22 arranged in opposition to each other may be located rearwardly of the roll 21 and serve to press the depending or suspended sides of the label into firm adhesive engagement with each other as illustrated in Fig. 4, thus producing the finished article as illustrated in Fig. 5 wherein the labels encircle the article 18 and have opposed sides arranged to adhesively engage each other. The label strip and the article 18 can be fed either intermittently or continuously but I find that very little advantage is derived from intermittent feeding. By timing the speed of operation of the windup reel for the backing with relation to the speed of advancement of the article 18, the interval between consecutive labels on the finished article can be regulated. In this manner labels may be applied to endless elongated articles at regular intervals very speedily and efficiently.

It is not necessary in all instances that the dispenser be arcuately shaped as illustrated in Fig. 2. This form is preferred particularly when the label material is very thin and highly flexible in that it tends to stiffen the label by the transverse arching when the backing is stripped therefrom. However, if the label material is adequately stiff or thick so that there is no tendency for it to follow the backing around the peeling edge 13 the dispenser may be flat as illustrated in Fig. 7, wherein there is an upper passage 11a and a lower passage 11b between which is arranged the peeling edge formed at the rear end of the partition 13a. The label strip is fed rearwardly through the upper passage 11a and its backing strip is then drawn around the peeling edge forwardly through the lower passage 11b. The labels 16a are consecutively peeled or stripped from the backing and are deposited on the article 18. In this form of construction as previously explained if the article is of relatively large diameter as compared with the size of the label the grooved roll 21 may alone be employed to firmly press the label into firm adhesive engagement with the article. On the other hand, if the article is of relatively small diameter rolls 22 may be required in addition to the roll 21 to press the suspended sides of the label into engagement with each other as illustrated in Fig. 4.

It will be appreciated from the above-described construction that the present invention enables pressure-sensitive labels to be rapidly fed by means of their backing strip to a dispensing mechanism and to be consecutively stripped or peeled therefrom and deposited on an elongated article which may be continuously fed adjacent the dispenser. By adjusting the timing the interval between consecutive labels applied to the article may be varied to any desired distance.

Various changes may be made in the details of construction without departing from the spirit

or scope of the invention as defined by the appended claims.

I claim:

1. The method of applying labels to an elongated article which consists of feeding a label strip having labels temporarily attached to a backing to a dispenser which consecutively separates the labels from the backing and feeding an elongated article adjacent the dispenser so as to receive the separated labels upon their being separated from the backing, pressing the labels downwardly around the sides of the elongated article and pressing the suspended sides of the labels into mutual engagement beneath the article.

2. Means for applying labels to wire, cord, and like articles comprising peeling means across which a label strip may be fed to peel the backing of the strip from the labels mounted thereon, means for feeding the wire or the like adjacent said peeling means so as to have deposited thereon the detached labels, and means for bending the labels around the wire so as to have the opposed sides thereof adhesively engaged.

3. Means for applying labels to wire, cord, and like articles comprising peeling means across which a label strip may be fed to peel the backing of the strip from the labels mounted thereon, means for feeding the wire or the like adjacent said guide means so as to have deposited thereon the detached labels, and means for forcing the detached labels into firm adhesive engagement with the wire or the like.

4. Means for applying labels to wire, rope and like articles comprising means forming an arcuate passage through which a label strip may be fed to peel the backing of the strip from the labels mounted thereon, a peeling edge at the rear of said passage, peeling means for the backing extending forwardly from said peeling edge, and means for feeding the wire or the like beneath said guide means so as to have deposited thereon the detached labels.

5. Means for applying labels to wire, rope, and like articles comprising means forming an arcuate passage through which a label strip may be fed to peel the backing of the strip from the labels mounted thereon, a peeling edge at the rear of said passage, guide means for the backing extending forwardly from said peeling edge, means for feeding the wire or the like beneath said guide means so as to have deposited thereon the detached labels, and means for forcing the detached labels into firm adhesive engagement with the wire or the like.

6. Means for applying labels to wire, rope, and the like comprising means providing an arcuate peeling edge, means for feeding a label strip having labels temporarily applied thereto by means of pressure-sensitive adhesive towards said peeling edge, means for drawing the backing of the label strip around the peeling edge to detach the labels therefrom, and means for feeding the wire, rope, or the like under said arcuate peeling edge.

7. Means for applying labels to wire, rope, and the like comprising means providing an arcuate peeling edge, means for feeding a label strip having labels temporarily applied thereto by means of pressure-sensitive adhesive towards said peeling edge, means for drawing the backing of the label strip around the peeling edge to detach the labels therefrom, means for feeding the wire, rope, or the like under said arcuate peeling edge, and means for forcing the detached labels into

firm adhesive engagement with the wire or the like.

8. Means for applying labels to wire, rope, and the like comprising means providing an arcuate peeling edge, means for feeding a label strip having labels temporarily applied thereto by means of pressure-sensitive adhesive towards said peeling edge, means for drawing the backing

5 of the label strip around the peeling edge to detach the labels therefrom, means for feeding the wire, rope, or the like under said arcuate peeling edge, and means for forcing opposed sides of the labels into mutual engagement with each other encircling the wire, rope, or the like.

RAY STANTON AVERY.
